UNITED STATES PATENT OFFICE.

JOHN J. JACOBS, OF NEW YORK, N. Y.

COUPLING.

1,284,692.

Specification of Letters Patent. Patented Nov. 12, 1918.

Application filed July 15, 1916, Serial No. 109,474. Renewed July 19, 1918. Serial No. 245,783.

To all whom it may concern:

Be it known that I, JOHN J. JACOBS, a citizen of the United States, and a resident of the city of New York, borough of Manhattan, in the county and State of New York, have invented a new and Improved Coupling, of which the following is a full, clear, and exact description.

The invention relates to harness straps, belts, suspenders and similar articles.

The object of the invention is to provide a new and improved coupling connection for connecting a strap or a belt with a buckle, trace hook or a similar device and arranged to dispense with doubled-up portions of the strap or belt, and stitches for fastening the parts together thus greatly reducing the cost of manufacture both in labor and in material.

In order to accomplish the desired result, use is made of a coupling member having a loop for engagement with one of the parts to be coupled together, the coupling member having side plates provided with registering slots, and a double button adapted to be attached to the other part and provided at its ends with heads engaging the said slots.

A practical embodiment of the invention is represented in the accompanying drawings forming a part of this specification, in which similar characters of reference indicate corresponding parts in all the views.

Figure 1 is a perspective view of the coupling or connection as applied to a belt for attaching the buckle to one end thereof.

Fig. 2 is an enlarged face view of the same with the retaining loop in section;

Fig. 3 is a sectional plan view of the same on the line 3—3 of Fig. 2;

Fig. 4 is a sectional face view of the same with the strap turned into an angular position relative to the coupling member; and

Fig. 5 is a face view of the blank for forming the coupling member.

As illustrated in the drawings, one end of a belt or strap 10 is connected with a buckle 11 by the use of a coupling member 12 and a stud or a button 13. The coupling member 12 is preferably made from a rectangular piece of sheet metal doubled up to form a loop or an eye 14 and side plates 15 and 16 spaced apart for receiving one end of the strap or belt 10 between them. The loop or eye 14 engages the rear crossbar 17 of the buckle 11, and the said loop or eye

is provided at its middle with a cut-out portion 18 to accommodate the eye 19 of the buckle tongue 20 mounted to swing on the rear crossbar 17 in the usual manner. 60

The stud or button 13 extends in an aperture 21 formed in the end portion of the belt or strap 10 extending between the side plates 15 and 16, and the said stud or button 13 is provided at its end with annular 65 grooves 22 and 23 adapted to engage the walls of the keyhole slots 24, 25 formed in the side plates 15 and 16 and located directly opposite each other so as to be in register with each other. It is understood that the 70 grooves 22 and 23 in the stud or button 13 provide the latter with heads to project on the outer face of the side plates 15 and 16 to securely attach the side plates to the belt or strap. The stud 13 is located in the strap 75 or belt 10 a distance from the end thereof so that when the parts are fastened together the terminal of the strap or belt 10 abuts against the crossbar 17 of the buckle 11.

In assembling the parts, the coupling 80 member 12 is engaged with the crossbar 17 of the buckle 11 and the stud 13 is engaged with the belt or strap 10, and then the end of the strap with the stud therein is passed between the side plates 15 85 and 16 with the belt or strap standing approximately at a right angle to the longitudinal center of the buckle 11, as indicated in Fig. 4. The heads of the stud 13 are passed through the enlarged ends of 90 the keyhole slots 24 and 25 and then the belt or strap 10 is moved outward to the left so as to engage the grooves 22 and 23 with the walls of the narrow portions of the slots 24 and 25. The belt or strap 10 is now given 95 a quarter turn on the stud 13 as the fulcrum to move the belt or strap into alignment with the buckle 11. In order to readily permit this turning movement of the belt or strap 10, one corner thereof is preferably rounded 100 off, as indicated at 26 in Fig. 4, but this is not absolutely necessary as the leather or other similar material of which the belt or strap 10 is made yields sufficiently to let the belt pass into longitudinal position relatively to the buckle 11. The end of the belt may also be provided with a notch 27 for accommodating the eye 19 to allow free movement thereof and to hold the belt 10 against turning movement on the stud or 110 button 13. It will be noticed that the pull on the free end of the buckle by the free end

of the belt or strap tends to hold the button or stud 13 in engagement with the narrow portions of the registering keyhole slots 24 and 25 so that the button is not liable to 5 be accidentally disengaged from the side plates 15 and 16.

A retaining loop 30 of leather or other flexible material extends around the side plates 15 and 16 and is adapted to receive 10 and retain the free end of the belt or strap 10. In order to hold the retaining loop 30 from moving out of position use is made of a flange 31 struck up at the end of the plate 16 for engagement with the adjacent edge 15 of the loop 30 (see Fig. 3) to hold the latter in position on the member 12.

The coupling connection shown and described is very simple in construction as it is practically composed of but two parts, 20 that is, the coupling member 12 and the stud 13 and the parts can be readily assembled to securely attach a buckle 11 or a similar device to one end of a belt or strap and without resorting to doubling up the end portions 25 of the belt or strap and sewing the same together after the buckle is placed in position, as heretofore practised.

Having thus described my invention, I claim as new and desire to secure by Letters 30 Patent:

1. A coupling for buckle straps and similar articles, comprising a coupling member having a loop for engagement with one of the parts to be coupled together, the coupling member having side plates provided 35 with registering slots, and a double button adapted to be attached to the other part and provided at its ends with heads engaging the said slots.

40 2. A coupling for buckle straps and similar articles, comprising a coupling member made of a single piece of sheet metal doubled up to form a loop and side plates, the loop being adapted to be engaged with the buckle 45 and the side plates being spaced apart for

the reception of one end of the strap, the said side members having registering keyhole slots, and a button held in the strap and having heads at the ends projecting beyond the faces of the strap and engaging the said 50 slots.

3. A coupling for buckle straps and similar articles, comprising a coupling member made of a single piece of sheet metal doubled up to form a loop and side plates, the loop 55 being adapted to be engaged with the buckle and the side plates being spaced apart for the reception of one end of the strap, the said side members having registering keyhole slots, and a button held in the strap and 60 provided at its ends with annular grooves to form heads, the said grooves engaging the walls of the said keyhole slots.

4. A coupling for buckle straps and similar articles, comprising a coupling member 65 having a loop for engagement with one of the parts to be coupled together, the coupling member having side plates provided with registering slots, a double button adapted to be attached to the other part and provided at its ends with heads engaging the 70 said slots, a retaining loop through which extend the said side plates, and means on the coupling member engaging the said retaining loop to hold the latter in place. 75

5. A coupling for buckle straps and similar articles, comprising a coupling member made of a single piece of sheet metal doubled up to form a loop and side plates, the loop being adapted to be engaged with the buckle 80 and the side plates being spaced apart for the reception of one end of the strap, the said side members having registering keyhole slots and one of the side plates having a turned up flange, a button held in the strap 85 and engaging the said slots, and a retaining loop through which extend the said side plates, the said flange engaging one edge of the retaining loop.

JOHN J. JACOBS.
